HEAT AND LIGHT CONCENTRATING
HOLDER FOR ILLUMINATED DECORA-
TIVE LIGHTING DEVICESLouis Barnett, Brooklyn, N. Y., assignor to Ray-
lite Electric Corp., Long Island City, N. Y., a
corporation of New York

Application June 9, 1945, Serial No. 598,568

5 Claims. (Cl. 240—10)

1

This invention relates to improvements in illuminated ornamental devices and more particularly is directed to a heat and light concentrating holder means for confining heat and projecting light passing from an incandescent lamp to a liquid column for forming an illuminated vapor bubbling or unbroken stream display effect, such as used for trimming Christmas trees or decorative lighting, signs or the like.

Among the objects of the invention is to generally improve devices of the character described which shall be exceedingly simple in construction, of few parts, which shall be easy to assemble in effective position, which shall be cheap to manufacture, and which shall be practical and efficient to a high degree in use.

Other objects of this invention will in part be obvious and in part hereinafter pointed out.

The invention accordingly consists in the features of construction, combinations of elements and arrangements of parts which will be exemplified in the construction hereinafter described and of which the scope of application will be indicated in the following claims.

In the accompanying drawings, in which is shown various possible illustrative embodiments of this invention:

Fig. 1 is a front elevational view of an assembled unit of a Christmas tree lighting unit, shown partly broken away to expose the interior, constructed to embody the invention.

Figs. 2 and 3 are cross sectional views taken on lines 2—2 and 3—3, respectively, in Fig. 1, and

Fig. 4 is a perspective view, showing the improved heat and light concentrating holder removed from the lighting unit.

Referring in detail to the drawing, 10 denotes an illuminated ornamental device adapted to be used to trim a Christmas tree or the like, having incorporated in the assembly thereof a heat and light concentrating holder member 11 constructed to embody the invention.

Said holder member 11 as seen in Figs. 1 and 4, comprises a sleeve connector supporting in vertically upright position, a transparent tube body of glass or other translucent material designated generally as 12, said tube body 12 having an integral closed lower or bottom end 12a and sealed top end 12b. The closed bottom end 12a is fitted into the upper end 11a of said holder member 11, so that the lower or bottom tube end 12a is firmly supported in close proximity to a bulb 13a of an incandescent lamp 13, the lamp bulb 13a being fitted up into the lower end 11b of said holder member 11 thereby providing a relatively firm interconnecting support or rigid coupling.

The lamp 13 as here shown is mounted in one electric socket 16 of a Christmas tree lighting outfit of a well understood construction (not shown).

The tube body 12 may contain a readily vola-

2

tilizable liquid 14, such as ether or wood alcohol but preferably a translucent liquid which has a like relatively normal low boiling point but which is non-inflammable. The liquid 14 may be placed in the tube body 12 through the top end 12b thereof before fusing the latter for hermetically sealing in liquid 14 therein as shown in Fig. 1. The space 15 above the liquid 14 in the tube body 12 may be evacuated before said tube top end 12b is sealed to permit lowering the boiling point normally required for the liquid 14. Said space 15 constitutes a condensing and heat dissipating means.

As seen from Fig. 1, the invention is shown incorporated in the assembly of the ornamental illuminated device 10 as above described, said sleeve connecting holder member 11 being preferably made of any suitable material having light conducting properties of a high degree efficiency as for example quartz, or any well known molded plastic having similar characteristics, such as "Lucite." The lower end 11b of holder member 11 may be provided with spaced wing sections 11c which are inwardly bent to have rim edge surfaces 11d positioned in horizontal alignment with filament 13b in lamp bulb 13a. The upper end 11a of said holder member 11 may be formed or terminate with integral resilient spaced gripper portions 11e which may also be inwardly bent preferably in suitable angular relation to the axis of the tube body 12 and liquid column 14 so that light beams from the glowing lamp filament 13b which are caught by said edges 11d are transmitted longitudinally through the holder 11 and projected from terminating rim edge surfaces 11f of gripper portions 11e into the liquid column 14, as is clear from Fig. 1.

In practising the invention, assume an electric socket 16 is provided or arranged for decorative display lighting purposes and connected to a suitable power supply source (not shown) in the well understood manner for lighting the lamp 13. Heat and light radiated from the lamp filament 13b may be made effective to cause the generating of vapor 17 either in form of a continuous flow of bubbles, or in an unbroken stream current through the liquid column 14. The sleeve holder 11 which mounts the tube body 12 on the lamp bulb 13a, serves to guide and confine the heat conducting medium, namely, air therebetween so that a minimum of heat producing source will be necessary. The light transmission provided by the improved construction of said sleeve holder 11 above described, increases the light available by projecting therethrough light beams directly from the lamp filament 13a into the liquid column 14, in addition to light beams from lamp filament 13b which are projected longitudinally the length of the holder 11 into flowing bubbles or current 17 as seen from the ex-

terior of the tube body 12 and shown in Fig. 1. This increased illumination from the lamp filament 13b by two separate paths one of which by-passes the bottom tube end 12a and is transmitted through holder member 11 is particularly desirable when a bubble or current forming means forms an obstruction of the direct rays from the lamp filament 13b, or is opaque to the direct passage of light in which case substantially all the illumination to said bubble or current flow 17 is circuited through said sleeve member 11 as described above and is clearly shown in the drawing.

By coloring the material forming sleeve member 11 a wide range of color effects are made available beside the variegated lighting, produced at and around the openings in the regions of the spaced gripper portions 11e and spaced wing sections 11c.

It is also to be understood that holder member 11 may be made to conform to any requirement of design desired such as of straight line contour or of bulbous character. This feature is made possible because the light conducting material forms a path through said holder member 11 and is not affected by the shape thereof intermediate rim edge surfaces 11f of gripper portions 11e and rim edge surfaces 11d of wing sections 11c.

It also is contemplated in practising the invention described herein to apply same to holder fitting such as shown in Patent No. 2,378,934, issued June 26, 1945, to Joseph H. Kloner. In such case the incandescent lamp is mounted at right angles with respect to the tube body, such holder fitting being constructed of molded plastic, as for example "Lucite" and is formed to transmit light from the lamp filament through the molded plastic material as well as directly through the extension holder supporting the tube body in the same manner as above described for member 11.

It is thus seen that there is provided an improved heat and light concentrating holder means of the character described in which the objects of the invention are achieved and which are well adapted to meet all conditions of practical use.

As various possible embodiments may be made in the above invention for use for different purposes and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A device of the character described comprising an elongated sealed transparent tube body partially filled with a liquid column, said body being constructed and arranged to generate activated vapors for producing lighting effects passing through the liquid column on positioning an incandescent lamp having a glowing filament exteriorly at one end of said tube body, and a light transmitting member for supportingly

mounting the tube body over said lamp so that heat from said filament is guided and confined to generate said vapors, said member having portions turned toward the filament and tube body to transmit light beams emitted by said filament and for directing same through the tube body and hence into the liquid column for illuminating the activated vapors.

2. A holder of the character described comprising a light transmitting sleeve member for mounting a transparent tube body with a volatile liquid column therein over an incandescent lamp having the filament and for guiding and confining illuminated radiant heat from said filament to generated flowing vapors in said liquid column, portions of said sleeve member being bent to receive direct light from said filament for transmitting same through said member and bent to direct said light into the tube body in addition to illumination received with said guided and confined radiant heat.

3. A device as defined in claim 1 in which said holder member is formed of one piece having a resilient end structure for engaging said ornament and forming said portions.

4. A device of the character described comprising a tubular structure formed of light condensing and guiding material one end of said structure having integral holder means for mounting a decorative ornament containing a vaporizing liquid, the other end of said structure having a portion turned to receive light beams from a glowing heat producing filament for transmission through said structure, said first mentioned end being turned to transmit light beams passing therethrough into said ornament.

5. A device of the character described comprising heat and light concentrator holder member for supportingly mounting an illuminated decorative display ornament over a glowing heat radiating means, said member having means extending between said heat radiating means to an end of the ornament for confining and guiding heat from said radiating means to a liquid vaporizing region of said ornament end, and light projecting means for transmitting light from said glowing means in a plurality of paths into said ornament, said light projecting means having portions forming said paths turned toward the glowing means and turned toward said ornament end.
